UNITED STATES PATENT OFFICE

EMIL G. ZULLIG, OF BERGENFIELD, NEW JERSEY, ASSIGNOR TO SAMUEL ELLEN, OF NEW YORK, N. Y.

DESIGN FOR A COMBINED CUFF AND SLEEVE EMBROIDERED TEXTILE FABRIC

Application filed December 30, 1931. Serial No. 42,318. Term of patent 3½ years.

To all whom it may concern:

Be it known that I, EMIL G. ZULLIG, a citizen of the United States, residing in Bergenfield, in the county of Bergen and State of New Jersey, have invented a new, original and ornamental Design for a Combined Cuff and Sleeve Embroidered Textile Fabric, of which the following is a specification, reference being had to the accompanying drawing, forming part thereof:

The figure is a plan view of a combined cuff and sleeve embroidered textile fabric, showing my new design.

I claim:

The ornamental design for a combined cuff and sleeve embroidered textile fabric substantially as shown.

EMIL G. ZULLIG.
